United States Patent Office

Des. 181,415
Patented Nov. 12, 1957

181,415

FINGER RING OR THE LIKE

Ronald C. Hentges and Eli Friedman, Los Angeles, Calif.,
assignors to H. & F. Jewelry Manufacturing, Inc., Los
Angeles, Calif., a corporation of California

Application March 4, 1957, Serial No. 45,081

Term of patent 14 years

(Cl. D45—10)

FIG. 1.

FIG. 2.

FIG. 3.

FIG. 4.

FIG. 6.

Figure 1 is a top plan view of a finger ring or the like, showing our new design;

Figure 2 is an end elevational view;

Figure 3 is a side elevational view;

Figure 4 is a side elevational view opposite that shown in Figure 3;

Figure 5 is an end elevational view of the end opposite that shown in Figure 2; and

Figure 6 is a bottom plan view.

We claim:

The ornamental design for a finger ring or the like, as shown.
